HIGH PERFORMANCE FLAT PANEL ANTENNAS FOR DUAL BAND, WIDE BAND AND DUAL POLARITY OPERATION

CLAIM OF PRIORITY

The present application is a 35 U.S.C. § 371 national stage application of PCT Application No. PCT/US2017/047545, filed on Aug. 18, 2017, which itself claims the benefit of and priority under 35 U.S.C. § 119 to U.S. Provisional Patent Application No. 62/384,829, filed Sep. 8, 2016, the entire contents of which are incorporated by reference herein in their entireties. The above-referenced PCT Application was published in the English language as International Publication No. WO 2018/048605 A1 on Mar. 15, 2018.

FIELD

The present invention relates generally to communications systems and, more particularly, to flat panel antennas utilized in microwave communications systems.

BACKGROUND

Flat panel antennas technology may not be extensively used in the licensed commercial microwave point-to-point or point-to-multipoint market, where more stringent electromagnetic radiation envelope characteristics consistent with efficient spectrum management may be more common. Antenna solutions derived from traditional reflector antenna configurations, such as prime focus fed axi-symmetric geometries, can provide high levels of antenna directivity and gain at relatively low cost. However, the extensive structure of a reflector dish and associated feed may require enhanced support structure to withstand wind loads, which may increase overall costs. Further, the increased size of reflector antenna assemblies and the support structure required may be viewed as a visual blight.

Flat panel arrays may be formed, for example, using waveguide or printed slot arrays in resonant or travelling wave configurations. Resonant configurations typically cannot achieve the desired electromagnetic characteristics over the bandwidths utilized in the terrestrial point-to-point market sector, while travelling wave arrays typically provide a main beam radiation pattern which moves in angular position with frequency. Because terrestrial point-to-point communications generally operate with transmit/receive channels spaced over different parts of the frequency band being utilized, movement of the main beam with respect to frequency may prevent simultaneous efficient alignment of the link for both channels.

When used in wide-band applications, especially in dual polarization operation, conventional flat panel antennas having high electrical performance, low production costs and low complexity may be difficult to design. Additional equipment such as diplexers may result in undesirable increases in system complexity.

SUMMARY

Some embodiments of the inventive concept are flat panel antennas. For example, a flat panel antenna may include a plurality of flat panel arrays (FPAs) that are arranged adjacent one another. Some embodiments provide that ones of the plurality of FPAs are configured to radiate in a plurality of different respective frequency bands and/or at different

respective polarizations. The antenna may include an enclosure that defines an internal cavity that includes the plurality of FPAs.

In some embodiments, the plurality of FPAs comprises a first FPA that is operable to radiate electromagnetic energy having a vertical polarization and a second FPA that is operable to radiate electromagnetic energy having a horizontal polarization. Some embodiments provide that the plurality of FPAs comprise a first FPA that is configured to exclusively operate in a transmit mode and a second FPA that is configured to exclusively operate in a receive mode.

In some embodiments, the plurality of FPAs comprise a first FPA that is configured to operate in a first frequency band and a second FPA that is configured to operate in a second frequency band that is different from the first frequency band. Some embodiments provide that the first frequency band and the second frequency band are narrow bands. In some embodiments, the first frequency band comprises a 71-76 GHz frequency band and the second frequency band comprises a 81-86 GHz frequency band. Some embodiments provide that the first frequency band and the second frequency band combine to transmit and/or receive electromagnetic energy in a wide band.

In some embodiments, the plurality of FPAs comprise a first FPA that is configured to operate in a first frequency band and a second FPA that is operable to radiate electromagnetic energy in the first frequency band. In some embodiments, a polarization of the first FPA may be orthogonal relative to a polarization of the second FPA. In some embodiments, the polarization difference between the first FPA and the second FPA is about ninety degrees.

Some embodiments provide that the plurality of FPAs further comprise a third FPA that is configured to operate in a second frequency band and a fourth FPA that is operable to radiate electromagnetic energy in the second frequency band. In some embodiments, a polarization of the third FPA may be orthogonal relative to a polarization of the fourth FPA. In some embodiments, the polarization difference between the third FPA and the fourth FPA is about ninety degrees.

In some embodiments, the plurality of FPAs comprise a first FPA that is operable to transmit and/or receive electromagnetic energy having a vertical polarization in a first frequency band, a second FPA that is operable to transmit and/or receive electromagnetic energy having a horizontal polarization in the first frequency band, a third FPA that is operable to transmit and/or receive electromagnetic energy having the vertical polarization in a second frequency band that is different from the first frequency band and a fourth FPA that is operable to transmit and/or receive electromagnetic energy having the horizontal polarization in the second frequency band.

Some embodiments provide that the first FPA and the third FPA are configured to be coupled to a first radio and the second FPA and the fourth FPA are configured to be coupled to a second radio. In some embodiments, the first FPA and the third FPA are configured to transmit the electromagnetic energy and the second FPA and the fourth FPA are configured to receive the electromagnetic energy. In some embodiments, the first, second, third and fourth FPAs are arranged in a two column, two row configuration. Some embodiments provide that the second FPA is in a first row and a first column, the third FPA is in the first row and a second column, the fourth FPA is in a second row and the first column, and the first FPA is in the second row and the second column.

In some embodiments, each of the plurality of FPAs is a rectangular shaped FPA and has a polarization direction that extends diagonally across the rectangular shaped FPA from a first corner to a second corner that is opposite the first corner. Some embodiments provide that the plurality of FPAs comprise a first FPA that is operable to transmit and/or receive electromagnetic energy having a vertical polarization in a first frequency band, a second FPA that is operable to transmit and/or receive electromagnetic energy having a horizontal polarization in the first frequency band, a third FPA that is operable to transmit and/or receive electromagnetic energy having the vertical polarization in a second frequency band that is different from the first frequency band and a fourth FPA that is operable to transmit and/or receive electromagnetic energy having the horizontal polarization in the second frequency band.

Some embodiments provide that the plurality of FPAs are arranged in a diamond shaped configuration and the enclosure is substantially rectangular and is arranged such that a corner of each of the plurality of FPAs is positioned along a corresponding side of the enclosure.

In some embodiments, the plurality of FPAs are arranged in a diamond shaped configuration and the enclosure is substantially diamond shaped and is arranged such that each corner of the enclosure is positioned adjacent a corner of a different one of the plurality of FPAs.

In some embodiments, the plurality of FPAs comprise a first FPA that is configured to operate in a first frequency band and a second FPA that is configured to operate in a second frequency band that is different from the first frequency band. In some embodiments the antenna may further include a first radio that is coupled to the first FPA, a second radio that is coupled to the second FPA and a diplexer that is coupled to the first radio and the second radio.

Some embodiments provide that the first frequency band and the second frequency band are each a narrow frequency band channel and that the diplexer is operable to combine a first frequency band channel from the first radio and a second frequency band channel from the second radio into a wideband channel in a receive mode.

In some embodiments, the first frequency band and the second frequency band are each a narrow frequency band channel and the diplexer is operable to separate a wideband channel into a first frequency band channel and a second frequency band channel in a transmit mode.

Some embodiments further include at least one electromagnetic decoupling structure that is positioned adjacent one or more of the plurality of FPAs and that is configured to reduced electromagnetic interference between ones of the plurality of FPAs.

In some embodiments, the enclosure comprises a radio mounting structure that is configured to attach at least one radio that is coupled to at least one of the plurality of FPAs to the flat panel antenna.

Some embodiments of the present inventive concept are directed to methods of manufacturing a flat panel antenna. Such methods may include providing a plurality of flat panel arrays (FPAs) that are arranged adjacent one another, wherein ones of the plurality of are configured to operate in a plurality of different respective frequency bands and/or at different respective polarizations and providing, an enclosure that defines an internal cavity that includes the plurality of FPAs.

BRIEF DESCRIPTION OF THE DRAWINGS

The accompanying drawings, which are incorporated in and constitute a part of this specification, illustrate embodi-

ments of the invention, where like reference numbers in the drawing figures refer to the same feature or element and may not be described in detail for every drawing figure in which they appear and, together with a general description of the invention given, above, and the detailed description of the embodiments given below, serve to explain the principles of the invention.

FIG. 1 is a schematic isometric angled front view of a conventional flat panel antenna.

10 FIG. 2 is a schematic block diagram illustrating a flat panel antenna for dual band, wide band and dual polarity operation according to some embodiments of the present invention.

15 FIG. 3 is a schematic diagram illustrating a flat panel antenna for dual band, wide band and dual polarity operation according to some embodiments of the present invention.

20 FIG. 4 is a schematic diagram illustrating a diamond arrangement of a flat panel antenna for dual band, wide band and dual polarity operation according to some embodiments of the present invention.

25 FIG. 5 is a schematic diagram illustrating another diamond arrangement of a flat panel antenna for dual band, wide band and dual polarity operation according to some embodiments of the present invention.

30 FIG. 6 is a schematic block diagram illustrating a flat panel antenna for single band and dual polarity operation according to some embodiments of the present invention.

35 FIG. 7 is a schematic block diagram illustrating a flat panel antenna for dual band and selectable polarity operation according to some embodiments of the present invention.

40 FIG. 8A is a schematic block diagram illustrating a conventional dual band antenna system using a single antenna.

45 FIG. 8B is a schematic block diagram illustrating a dual band antenna system using a flat panel antenna having multiple antenna arrays according to some embodiments of the present invention.

50 FIG. 9A is a schematic block diagram illustrating a conventional antenna system using a diplexer to split a wide bandwidth channel into separate narrow bandwidth channels.

55 FIG. 9B is a schematic block diagram illustrating a dual band antenna system using a flat panel antenna having multiple antenna arrays according to some embodiments of the present invention.

60 FIG. 10A is a schematic block diagram illustrating a conventional duplexed antenna system.

65 FIG. 10B is a schematic block diagram illustrating a dual band or dual polarity antenna system using a flat panel antenna having multiple antenna arrays according to some embodiments of the present invention.

55 FIG. 11A is a schematic block diagram illustrating a conventional orthogonally polarized antenna system having two single polarization radios.

55 FIG. 11B is a schematic block diagram illustrating an orthogonally polarized antenna system having two single polarization radios and using a flat panel antenna having multiple antenna arrays according to some embodiments of the present invention.

60 FIG. 12A is a schematic block diagram illustrating a conventional orthogonally polarized antenna system having one dual polarization radio.

65 FIG. 12B is a schematic block diagram illustrating an orthogonally polarized antenna system having one dual polarization radio and using a flat panel antenna having multiple antenna arrays according to some embodiments of the present invention.

DETAILED DESCRIPTION

Flat panel array antennas may be formed in multiple layers via machining or casting. For example, U.S. Pat. No. 8,558,746 to Thomson et al. (the disclosure of which is hereby incorporated by reference herein in its entirety) discusses a flat panel array antenna constructed as a series of different layers. Shown therein are flat panel arrays that include input, intermediate and output layers, with some embodiments including one or more slot layers and one or more additional intermediate layers. The layers are manufactured separately (typically via machining or casting) and stacked to form a flat panel antenna having an integrated feed network.

Brief reference is made to FIG. 1, which is a schematic isometric angled front view off conventional flat panel antenna. As illustrated, a flat panel array antenna 10 may be formed from several layers each with surface contours and apertures combining to form a feed horn array and RF path comprising a series of enclosed coupling cavities and interconnecting waveguides when the layers are stacked upon one another.

The RF path may include a waveguide network coupling an input feed to a plurality of primary coupling cavities. Some embodiments provide that each of the primary coupling cavities may include four output ports that each may be coupled to a horn radiator 25.

The input feed may be positioned generally central on a first side 30 of an input layer 35, for example to allow compact mounting of a microwave transceiver thereto, using antenna mounting features (not shown) that may be interchangeable with those used with traditional reflector antennas. Some embodiments provide that, the input feed may be positioned at a layer sidewall between the input layer 35 and a first intermediate layer 45 enabling, for example, an antenna side by side with the transceiver configuration where the depth of the resulting flat panel antenna assembly may be reduced.

In some embodiments, a waveguide network may be provided on a second side 50 of the input layer 35 and a first side 30 of the first intermediate layer 45. Some embodiments provide that the waveguide network may be provided with a rectangular waveguide cross section, a long axis of the rectangular cross section normal to a surface plane of the input layer 35. In some embodiments, the waveguide network may be configured wherein a long axis of the rectangular cross section is parallel to a surface plane of the input layer 35 and/or may be configured wherein a long axis of the rectangular cross-section is parallel to a surface plane of the input layer 35. A seam 70 between the input layer 35 and the first intermediate layer 45 may be applied at a midpoint of the waveguide cross section.

The waveguide network may distribute the RF signals to and from the input feed to a plurality of primary coupling cavities provided on a second side, of the intermediate layer 45. The waveguide network may be dimensioned to provide an equivalent length electrical path to each primary coupling cavity to ensure common phase and amplitude. Some embodiments provide that the waveguide sidewalls of the waveguide network may also be provided with surface features for impedance matching, filtering and/or attenuation.

The output layer 75 may be a monolithic layer including the array of horn radiators 25 on the second side 50 thereof, and a plurality of output ports (not shown) for the primary coupling cavities on the first side that is opposite the second side 50. The output ports may be generally rectangular in

configuration, and multiple (for example, four) of the output ports may be coupled to each of the primary coupling cavities. Each of the output ports may also be coupled to one of the horn radiators 25 by one or more polarization rotator elements (not shown) that are integrated in the output layer 75. For example, the output ports, horn radiators 25, and polarization rotator elements may be machined into the monolithic output layer 75 from the first side and/or the second side 50 thereof.

In some embodiments described herein, the polarization rotator elements include one or more multi-sided slots or openings in the output layer 75 that couple each output port to one of the horn radiators 25. In some embodiments, the polarization rotator elements include elongated, generally diamond-shaped slots or openings. One of the generally diamond-shaped slots may be in communication with each of the output ports, and may couple each of the output ports to an inlet port at a base of one of the horn radiators 25. In some embodiments, the horn radiators 25, the inlet ports, the slots, the openings, and/or the output ports may include one or more radiused corners and/or ends resulting from the machining process.

The input layer 35, intermediate layer 45 and/or output layer 75 may be assembled using various techniques, including but not limited to mechanical fixings, brazing, diffusion bonding, and lamination. For example, two or more of the layers 35, 45, and/or 75 may be joined by a brazing process, using a filler metal (having a lower melting point than the layers) at the seams between the layers. Additionally or alternatively, two or more of the layers 35, 45, and/or 75 may be joined using a diffusion bonding process, by clamping two or more of the layers together with respective surfaces abutting, and applying pressure and heat to bond the layers. Such brazing and/or diffusion bonding processes can provide very good bonding between plates, which may result in lower electrical losses and/or reduced or minimized RF leakage. In some embodiments, two or more of the different layers may be formed as a monolithic unit.

As frequency increases, wavelengths decrease. Therefore, as the desired operating frequency increases, the physical features within a corporate waveguide network, such as steps, tapers and T-type power dividers, may become smaller and harder to fabricate. As use of the coupling cavities can simplify the waveguide network requirements, one skilled in the art will appreciate that higher operating frequencies are enabled by the present flat panel antenna.

It will be understood that, as described herein, various attributes of an antenna array, such as beam elevation angle, beam azimuth angle, and half power beam width, may be determined based on the magnitude and/or phase of the signal components that are fed to each of the radiating elements. The magnitude and/or phase of the signal components that are fed to each of the radiating elements may be adjusted so that the flat panel antenna will exhibit a desired antenna coverage pattern in terms of, for example, beam elevation angle, beam azimuth angle, and half power beam width. The desired frequency range of operation may determine the sizes, dimensions, and/or spacings of the elements of the antenna array.

Some embodiments of the present invention provide apparatus and methods that provide high performance antenna operation using, flat panel antennas that include multiple flat panel arrays in a single enclosure to provide multiple band, dual polarization performance as a single solution with less complex fabrication than a single array flat panel antenna to provide electrical performance approaching that of much larger traditional reflector antennas.

Reference is now made to FIG. 2, which is a schematic block diagram illustrating a flat panel antenna 100 for dual band, wide band and dual polarity operation according to some embodiments of the present invention. As illustrated, the flat panel antenna 100 may include a single enclosure 120 that includes an internal cavity in which multiple flat panel arrays (FPAs) 110 may be provided (namely, FPAs 110-A-110D). In some embodiments, the single enclosure includes a back panel, a plurality of sidewalls and a front panel. Any and/or all of the back panel, ones of the plurality of sidewalls and/or the front panel may be fixed relative to other ones thereof and/or may be removable to access the internal cavity and/or portions thereof. The back panel, ones of the plurality of sidewalls and/or the front panel may each include an electrically conductive material and/or an electrically insulating material, such as a dielectric material.

The multiple FPAs 110 may be arranged adjacent one another and may be configured to operate in a plurality of different respective frequency bands and/or at different respective polarizations. For example, as illustrated, FPA 110A may be configured to operate in a first frequency band and to transmit and/or receive electromagnetic energy having a vertical polarization, FPA 110B may be configured to operate in the first frequency band and to transmit and/or receive electromagnetic energy having a horizontal polarization, FPA 110C may be configured to operate in a second frequency band and to transmit and/or receive electromagnetic energy having a vertical polarization, and FPA 110D may be configured to operate in the second frequency band and to transmit and/or receive electromagnetic energy having a horizontal polarization.

In some embodiments, the flat panel antenna 100 may be used as a wideband dual polarization antenna. For example, in some embodiments, wide bandwidth, antennas are needed that operate in both the 71-76 GHz and 81-86 GHz frequency bands. The flat panel antenna 100 may accomplish this using different FPAs 110 that may be configured to operate in two different frequency bands. In this regard, FPAs 110A and 110B may each operate in the lower frequency band (i.e., first frequency band) of 71-76 GHz. Similarly, FPAs 110C and 110D may each operate in the upper frequency band (i.e., second frequency band) of 81-86 GHz. Some embodiments provide that the two different frequency bands are substantially non-adjacent on the frequency spectrum. For example, a first frequency band may be around 23 GHz while the second frequency band may be around 80 GHz. Such examples are non-limiting as the first and second frequency bands may include frequency bands that are lower than, higher than, and/or in between those listed herein.

Some embodiments provide that dual polarization operation may be achieved using different FPAs 110 that are configured to transmit and/or receive electromagnetic energy having different polarizations. As used herein, the polarization of an electromagnetic signal may refer to the approximate angle between the ground and the electric field of the electromagnetic signal. In some embodiments, the different polarizations may be substantially orthogonal relative to one another. For example, FPAs 110A and 110C may be operable to radiate electromagnetic energy having a substantially vertical polarization while FPAs 110B and 110D may be operable to radiate electromagnetic energy having a substantially horizontal polarization. While not illustrated in the current example, the different ones of the FPAs 110 may be +/-45 degrees versus vertical and horizontal, and/or may have right-handed circular polarization (RHCP) and/or left-handed circular polarization (LHCP).

Some embodiments provide that different ones of the FPAs 110 may be configured to operate exclusively in either a transmit mode or a receive mode. For example, as illustrated, FPA 110A may be configured to operate in a transmit mode and thus operate to transmit electromagnetic energy in the first frequency band having a vertical polarization and FPA 110B may be configured to operate in a receive mode and thus operate to receive electromagnetic energy in the first frequency band and having a horizontal polarization.

Similarly, FPA 110C may be configured to operate in a transmit mode and thus operate to transmit electromagnetic energy in the second frequency band and having a vertical polarization and FPA 110D may be configured to operate in receive mode and thus operate to receive electromagnetic energy in the second frequency band and having a horizontal polarization.

In some embodiments, the flat panel antenna 100 may include antenna circuitry 130 which may provide, interconnection, coordination, control and/or configuration of the FPAs 110. For example, various filters, duplexers, diplexers and/or orthomode transducers (OMTs) may be included in the flat panel antenna 100, depending on the desired mode of operation.

Although not illustrated, the flat panel antenna 100 may include an electromagnetic decoupling structure 111 that may include one or more metal and/or dielectric spacers within the enclosure 120 arranged relative to the different ones of the FPAs 110. In some embodiments, the metal and/or dielectric spacers may reduce or eliminate electromagnetic interference between different ones of the FPAs 110. Additionally, different ones of the FPAs 110 may include different polarizations and/or orientations to reduce and/or eliminate electromagnetic interference.

Brief reference is now made to FIG. 3, which is a schematic three-dimensional diagram illustrating a flat panel antenna 200 for dual band, wide band and dual polarity operation according to some embodiments of the present invention. The flat panel antenna 200 may include multiple FPAs 210 that may transmit and/or receive electromagnetic energy having different polarizations. For example, FPAs 210A and 210B may include radiators 225A that are shaped and oriented to transmit and/or receive electromagnetic energy that is horizontally polarized. In contrast, FPAs 210C and 210D may include radiators 225B that are shaped and oriented to transmit and/or receive electromagnetic energy that is vertically polarized. As discussed above regarding FIG. 2, some embodiments provide that some of the FPAs 210 are configured to operate in a first frequency band while other of the FPAs 210 may be configured to operate in a second frequency band that is different from the first frequency band. In some embodiments the first and second frequency bands may be substantially narrow frequency bands and may be substantially adjacent one another on a frequency spectrum. In some embodiments, the first frequency band and the second frequency band may be combined to transmit and/or receive electromagnetic energy in a wide band that includes multiple narrow frequency bands.

Reference is now made to FIG. 4, which is a schematic diagram illustrating a diamond arrangement of a flat panel antenna for dual band, wide band and dual polarity operation according to some embodiments of the present invention. A flat panel antenna 300 may include a plurality of FPAs 310 that may each be substantially square and/or rectangular and that each are operable to transmit and/or receive electromagnetic energy having a polarization that is diagonally oriented relative to the FPA 310. For example, the polariza-

tion direction may be generally arranged from corner to opposing corner of each FPA 310 instead of from side to opposing side thereof.

In some embodiments, each of the FPAs 310 may be oriented to present a diamond shape such that the diagonals of each FPA 310 define horizontal or vertical lines and the sides of each FPA 310 define an angle of about 45 degrees relative to the horizontal or vertical. Some embodiments provide that multiple FPAs 310 may be arranged in a generally diamond formation such that the shape of the combined FPAs 310 may define a diamond shape.

In some embodiments, the multiple FPAs 310 may include a top FPA 310A that is configured to operate in a first frequency band and to transmit and/or receive electromagnetic energy having a vertical polarization, FPA 310B may be configured to operate in a second frequency band and to transmit and/or receive electromagnetic energy having a vertical polarization, FPA 310C may be configured to operate in the second frequency band and to transmit and/or receive electromagnetic energy having a horizontal polarization, and FPA 310D may be configured to operate in the first frequency band and to transmit and/or receive electromagnetic energy having a horizontal polarization.

Some embodiments provide that the multiple FPAs 310 may be arranged in an enclosure 320. Some embodiments provide that the enclosure 320 is generally rectangular or square and may be dimensioned based on the height and width of the plurality of FPAs 310 that are arranged in the diamond formation.

Brief reference is now made to FIG. 5, which is a schematic diagram illustrating another diamond arrangement of a flat panel antenna for dual band, wide band and dual polarity operation according to some embodiments of the present invention. The flat panel antenna 400 may include multiple FPAs 410 that may be configured and arranged in a manner described above regarding FIG. 4. As such, additional discussion thereof will be omitted.

In contrast with the enclosure 320 of FIG. 4, the flat panel antenna 400 includes an enclosure 420 that is oriented to be in a diamond configuration that substantially matches the generally diamond formation corresponding to the shape of the combined FPAs 410. In this manner, the enclosure 420 may be sized smaller than that of enclosure 320 and thus may result in a reduced cost thereof.

In some embodiments, more than four of the FPAs may be included in a flat panel antenna. For example, some embodiments provide that 6, 8 or more FPAs may be included in a single flat panel antenna. Similarly, some embodiments provide that less than 4 FPAs may be used in a flat panel antenna. For example, brief reference is now made to FIG. 6, which is a schematic block diagram illustrating a flat panel antenna for single band and dual polarity operation according to some embodiments of the present invention. The flat panel antenna 600 may include at least two FPAs 610 that may be operable to transmit and/or receive electromagnetic energy having different polarizations in the same frequency band. For example, FPA 610A may be configured to transmit and/or receive electromagnetic energy having a substantially vertical polarization and 610B may be configured to transmit and/or receive electromagnetic energy having a substantially horizontal polarization.

In some embodiments, one of the FPAs 610 may be configured to operate in a transmit mode and the other one of the FPAs 610 may be configured to operate in a receive mode. Some embodiments provide that each of the FPAs 610 is configured to both transmit and receive. For example, operating both of the FPAs 610 in the same of the transmit,

receive and/or transmit and receive modes may provide redundant electromagnetic signals that provide an error correction function.

In some embodiments, the flat panel antenna 600 may include antenna circuitry 630 which may provide, interconnection, coordination, control and/or configuration of the FPAs 610. For example, various filters, duplexes, diplexers and/or orthomode transducers (OMTs) may be included in the flat panel antenna 600, depending on the desired mode of operation. As illustrated, the flat panel antenna 600 may include a single enclosure 620 that includes an internal cavity in which multiple flat panel arrays (FPAs) 610 may be provided. Other than dimensions, the enclosure 620 may include the same features as discussed above regarding FIG. 2. As such, additional description thereof will be omitted. In some embodiments, the single enclosure includes a back panel, a plurality of sidewalls and a front panel.

Brief reference is now made to FIG. 7, which is a schematic block diagram illustrating a flat panel antenna for dual band and selectable polarity operation according to some embodiments of the present invention. The flat panel antenna 700 may include at least two FPAs 710 that may be operable to transmit, and/or receive electromagnetic energy having different polarizations and in different frequency bands. For example, FPA 710A may be configured to transmit and/or receive electromagnetic energy having a substantially vertical polarization in a first frequency band and 710B may be configured to transmit and/or receive electromagnetic energy having a substantially horizontal polarization in a second frequency band that is different from the first frequency band.

In some embodiments, one of the FPAs 710 may be configured to operate in a transmit mode and the other one of the FPAs 710 may be configured to operate in a receive mode. Some embodiments provide that each of the FPAs 710 is configured to both transmit and receive. For example, operating both of the FPAs 710 in the same of the transmit, receive and/or transmit and receive modes may provide redundant electromagnetic signals that provide an error correction function.

In some embodiments, the flat panel antenna 700 may include antenna circuitry 730 which may provide, interconnection, coordination, control and/or configuration of the FPAs 710 which are described with reference to FIG. 6 above. As illustrated, the flat panel antenna 700 may include a single enclosure 720 that includes an internal cavity in which multiple flat panel arrays (FPAs) 710 may be provided. Other than dimensions, the enclosure 720 may include the same features as discussed above regarding FIG. 2. As such, additional description thereof will be omitted.

Additional cost or complexity corresponding to multiple FPAs may be recovered via benefits such as radio and/or system simplification, and/or antenna simplification. For example, single polarization FPAs may be simpler and thus less costly to manufacture than a dual polarization FPA. Some non-limiting examples of antennas and antenna systems including multiple FPAs are provided below in FIGS. 8A-12B, which compare conventional configurations and comparable configurations according to some embodiments herein.

Brief reference is now made to FIG. 8A, which is a schematic block diagram illustrating a conventional dual band antenna system. As illustrated, the dual band antenna system 810 includes a single antenna 10 operating across a substantially wide frequency band. The single antenna 10 may be coupled to a diplexer 816 via one or more bi-directional communication links 818. The diplexer 816 may

11

be further coupled to multiple radio modules **812** and **814** that are operable to transmit and receive communications in different respective frequency bands. For example, radio module **812** may be operable to transmit and receive communications in a first frequency band and radio module **814** may be operable to transmit in a second frequency band that is different from the first frequency band.

In use and operation, the diplexer **816** may be operable to separate two different frequency bands in the receive path and to combine the two different frequency bands in the transmit path. In such configurations, the frequency bands may be wide apart from one another in the frequency spectrum for the diplexer **816** to work satisfactorily. The diplexer **816** and radio modules **812** and **814** may be in a single radio **820** that may be in a single enclosure.

In contrast, reference is now made to FIG. 8B is a schematic block diagram illustrating a dual band antenna system using a flat panel antenna having multiple antenna arrays according to some embodiments of the present invention. As illustrated, the dual band antenna system **850** includes an antenna enclosure **870** that may include multiple different FPAs **800A**, **800B**. The FPAs **800A**, **800B** may be operable to transmit and/or receive electromagnetic energy in different frequency bands relative to one another. The FPAs **800A**, **800B** may be coupled to respective radio modules **822**, **824** that are operable to transmit and receive communications in the different respective frequency bands via respective bi-directional communication links **832**, **834**.

By using different FPAs **800A**, **800B**, the need for a diplexer and the cost and/or performance limitations corresponding to a diplexer may be avoided. For example, using separate FPAs **800A**, **800B** may reduce electromagnetic interference between the different frequency bands. As illustrated, the dual band antenna system **850** includes a dual band radio **871** that is separate from the antenna enclosure **870**, however, some embodiments provide that only a single enclosure **870** or **871** may be included and that the system components including FPAs **800A**, **800B**, communication links **832**, **834** and radio modules **822**, **824** may be mounted in and/or on the single enclosure **870** or **871**.

Reference is now made to FIGS. 9A and 9B, which are schematic block diagrams illustrating a conventional antenna system using a diplexer to split a wide bandwidth channel of a single antenna into separate narrow bandwidth channels and a dual band antenna system using a flat panel antenna having multiple antenna arrays according to some embodiments of the present invention, respectively. Reference is made to FIG. 9A, which illustrates a conventional antenna system **910** using an antenna **10** that is coupled to a wide bandwidth radio module **912** that is in a wide bandwidth radio **920** via one or more bi-directional communication links **908**. The wide bandwidth channel may include multiple narrow bandwidth channels that may include a first frequency band and a second frequency band. Some embodiments provide that the wide bandwidth radio module **912** and/or the antenna **10** may be mounted in and/or on the same enclosure.

Referring to FIG. 9B, a dual band antenna system **950** using a flat panel antenna having multiple antenna arrays may be provided according to some embodiments herein. As illustrated, the dual band antenna system **950** includes an antenna enclosure **970** that may include multiple different FPAs **900A**, **900B**. The FPAs **900A**, **900B** may be operable to transmit and/or receive electromagnetic energy in different frequency bands relative to one another. The FPAs **900A**, **900B** may be coupled to respective radio modules **918A**, **918B** that are operable to transmit and receive communica-

12

tions in the different respective frequency bands via respective bi-directional communication links **922A**, **922B**, respectively.

Each of the radio modules **918A**, **918B** may be coupled to a common diplexer **916** via respective bi-directional communication links **924A**, **924B**. By integrating the diplexer **916** into the interconnecting circuitry, the narrow bandwidth channels corresponding to the FPAs **900A**, **900B** and the radios **918A**, **918B** may be combined to provide a wide bandwidth channel, which may be processed by a wide bandwidth radio module **962** in a wide bandwidth radio **971**. In this manner, narrow band antenna performance may be provided for wide bandwidth channels. As illustrated, although the dual band antenna system **950** includes a separate enclosure **970** for the antenna and the radio **971**, some embodiments provide that only a single enclosure **970** or **971** may be included and that the antenna system components including FPAs **900A**, **900B**, communication links **922A**, **922B**, **924A**, **924B**, diplexer **916** and/or radio modules **918A**, **918B**, **962** may be mounted in and/or on the same enclosure **970**.

Reference is now made to FIG. 10A, which is a schematic block diagram illustrating a conventional duplexer antenna system using a single antenna and FIG. 10B, which is a schematic block diagram illustrating a dual band or dual polarity antenna system using a flat panel antenna having multiple antenna arrays according to some embodiments of the present invention. FIG. 10A illustrates a conventional duplexer antenna system **1010** using an antenna **10** that is coupled to a duplexer **1016** via one or more bi-directional communication links **1026**.

The duplexer **1016** may be coupled to a transmitter radio module **1012** using a first mono-directional communication link **1022** and a receiver radio module **1014** via a second mono-directional communication link **1024**. For example, the first mono-directional communication link **1022** may be operable to communicate a signal from the transmitter radio module **1012** to the duplexer **1016** and the second mono-directional communication link **1024** may be operable to communicate a signal from the duplexer **1016** to the receiver radio module **1014**. The duplexer **1016** may allow the use of the single antenna **10** by both the transmitter radio module **1012** and the receiver radio module **1014**. For example, the duplexer **1016** may couple the transmitter radio module **1012** and the receiver radio module **1014** to the antenna **10** while producing isolation between the transmitter radio module **1012** and the receiver radio module **1014**. Some embodiments provide that the duplexer **1016**, the transmitter radio module **1012**, the receiver radio module **1014** and/or the antenna **10** may be mounted in and/or on an enclosure **1020**.

Referring to FIG. 10B, dual band or dual polarity antenna system **1050** using a flat panel antenna having multiple antenna arrays is provided according to some embodiments herein. As illustrated, the dual band or dual polarity antenna system **1050** includes an antenna enclosure **1070** that may include multiple different FPAs **1000A**, **1000B**. The FPAs **1000A**, **1000B** may be configured to operate in different modes relative to one another. For example, FPA **1000A** may be operated exclusively in a transmission mode based on signals communicated from the transmitter radio module **1018A** via the mono-directional communication link **1028A**. In contrast, FPA **1000B** may be operated exclusively in a receive mode and may communicate received signals to the transmitter radio module **1018B** via the mono-directional communication link **1028B**.

In some embodiments, the FPAs **1000A**, **1000B** may be operated at the same frequencies and/or different frequencies relative to one another. Additionally, the FPAs **1000A**, **1000B** may radiate electromagnetic energy having the same polarization as one another and/or different polarizations relative to one another. By using two separate FPAs **1000A**, **1000B**, receive and transmit radio modules **1018A** and **1018B** may be used without a duplexer. In this manner the antenna system **1050** may include a more simple design and may provide improved performance by increasing the isolation between the transmitter radio module **1018A** and the receiver radio module **1018B**.

As illustrated, although the dual band antenna system **1050** includes an antenna enclosure **1070** the dual mode radio **1071** illustrated as separate components. However, some embodiments provide that some or all of the remaining components including FPAs **1000A**, **1000B**, communication links **1028A**, **1028B**, and/or radio modules such as transmitter radio module **1018A** and receiver radio module **1018B**, may be mounted in and/or on the same enclosure.

Reference is now made to FIG. 11A, which is a schematic block diagram illustrating a conventional orthogonally polarized antenna system having two single polarization radios and using an orthomode transducer and a single antenna and FIG. 11B, which is a schematic block diagram illustrating an orthogonally polarized antenna system having two single polarization radios and using a flat panel antenna having multiple antenna arrays according to sortie embodiments of the present invention. FIG. 11A illustrates a conventional orthogonally polarized antenna system **1110** that includes two single polarization radios **1120A**, **1120B**. For example, single polarization radio **1120A** includes a horizontal polarization radio module **1112** and single polarization radio **1120B** includes a vertical polarization radio module **1114**. Each of the horizontal and vertical polarization radio modules may be coupled to a single antenna **10** via an orthomode transducer (OMT) **1116** via one or more bi-directional communication links **1122**, **1124**, **1126**.

As used herein, an OMT **1116** may include a waveguide component that may combine and/or separate two orthogonally polarized microwave signal paths (i.e., horizontal and vertical). As illustrated, the OMT **1116** may be coupled to an antenna **10** via bidirectional communication link **1126** and to the horizontal radio module **1112** that is operable to transmit and receive signals corresponding electromagnetic energy that has a horizontal polarization via a bi-directional communication link **1122**. Additionally, the OMT **1116** may be coupled to the vertical radio module **1114** that is operable to transmit and receive signals corresponding to electromagnetic energy that has a horizontal polarization via a bi-directional communication link **1124**. By using the OMT **1116**, the antenna system **1110** may be operable to transmit and receive electromagnetic energy having both a horizontal and vertical polarization. The horizontal and vertical radio modules **1112**, **1114** may be included in separate respective radios **1120A**, **1120B**.

Reference is now made to FIG. 11B, which illustrates an orthogonally polarized antenna system **1150** having two single polarization radios **1171A**, **1171B** using a flat, panel, antenna having multiple antenna arrays is provided according to some embodiments herein. As illustrated, the orthogonally polarized antenna system **1150** includes an antenna enclosure **1070** that may include multiple different FPAs **1100A**, **1100B**. The FPAs **1100A**, **1100B** may be operable to transmit and/or receive electromagnetic energy having different polarizations relative to one another. For example, FPA **1100A** may radiate electromagnetic energy having a

horizontal polarization and FPA **1100B** may transmit and/or receive electromagnetic energy having a vertical polarization. Some embodiments provide that FPA **1100A** may receive and/or transmit horizontally polarized signals to/from a horizontal radio module **1118A** in radio **1171A** via a bi-directional communication link **1128A**. Similarly, some embodiments provide that FPA **1100B** may receive and/or transmit vertically polarized signals to/from the vertical radio module **1118B** in radio **1171B** via a bi-directional communication link **1128B**. In this manner, dual polarization operation may be provided using the FPAs **1100A**, **1100B** instead of requiring an OMT.

In some embodiments, the FPAs **1100A**, **1100B** may be operated at the same frequencies and/or different frequencies from one another. By using two separate FPAs **1100A**, **1100B**, horizontal and vertical radio modules **1118A** and **1118B** may be used without an OMT. In this manner the antenna system **1050** may include a more simple design and may provide improved performance by increasing the isolation between the horizontal radio module **1118A** and the vertical radio module **1118B**.

As illustrated, although the dual polarization antenna system **1150** includes separate enclosure **1170** and single polarization radios **1171A** and **1171B**, some embodiments provide that the components including FPAs **1100A**, **1100B**, communication links **1128A**, **1128B**, and/or radio modules **1118A**, **1118B**, may be mounted in and/or on a single enclosure.

Brief reference is now made to FIG. 12A, which is a schematic block diagram illustrating a conventional orthogonally polarized antenna system having one dual polarization radio and using a single antenna and FIG. 12B, which is a schematic block diagram illustrating an orthogonally polarized antenna system having one dual polarization radio and using a flat panel antenna having multiple antenna arrays according to some embodiments of the present invention.

FIG. 12A is similar to FIG. 11A except that instead of using two different single polarization radios **1171A**, **1171B** having respective horizontal and vertical radio modules **1118A**, **1118B**, FIG. 12A includes a dual polarization radio **1220** including both horizontal and vertical radio modules **1212**, **1214**. As such, additional description of FIG. 12A will be omitted.

Reference is made to FIG. 12B, which is similar to FIG. 11B except that instead of using two different single polarization radios **1120A**, **1120B** in FIG. 11, FIG. 12B includes one dual polarization radio **1271** that includes a horizontal radio module **1218A** and a vertical radio module **1218B** that are connected to the FPAs **1200A**, **1200B**, respectively, via bidirectional communication links **1222A**, **1222B**, respectively. As such, additional description of FIG. 12B will be omitted.

From the foregoing, it will be apparent that embodiments of the present invention provide a high performance flat panel antenna with improved dual-band, multiple polarization performance while reducing potential complexity and/or expense.

Embodiments of the present invention have been described above with reference to the accompanying drawings, in which embodiments of the invention are shown. This invention may, however, be embodied in many different forms and should not be construed as limited to the embodiments set forth herein. Rather, these embodiments are provided so that this disclosure will be thorough and complete,

15

and will fully convey the scope of the invention to those skilled in the art. Like numbers refer to like elements throughout.

It will be understood that, although the terms first, second, etc. may be used herein to describe various elements, these elements should not be limited by these terms. These terms are only used to distinguish one element from another. For example, a first element could be termed a second element, and, similarly, a second element could be termed a first element, without departing from the scope of the present invention. As used herein, the term "and/or" includes any and all combinations of one or more of the associated listed items.

It will be understood that when an element is referred to as being "on" another element, it can be directly on the other element or intervening elements may also be present. In contrast, when an element is referred to as being "directly on" another element, there are no intervening elements present. It will also be understood that when an element is referred to as being "connected" or "coupled" to another element, it can be directly connected or coupled to the other element or intervening elements may be present. In contrast, when an element is referred to as being "directly connected" or "directly coupled" to another element, there are no intervening elements present. Other words used to describe the relationship between elements should be interpreted in a like fashion (i.e., "between" versus "directly between", "adjacent" versus "directly adjacent", etc.).

Relative terms such as "below" or "above" or "upper" or "lower" or "horizontal" or "vertical" may be used herein to describe a relationship of one element, layer or region to another element, layer or region as illustrated in the figures. It will be understood that these terms are intended to encompass different orientations of the device in addition to the orientation depicted in the figures.

Unless otherwise defined, all technical and scientific terms used herein have the same meaning as commonly understood by one of ordinary skill in the art to which this invention belongs. The terminology used herein is for the purpose of describing particular embodiments only and is not intended to be limiting of the invention. As used herein, the singular forms "a", "an" and "the" are intended to include the plural forms as well, unless the context clearly indicates otherwise. It will be further understood that the terms "comprises" "comprising," "includes" and/or "including" when used herein, specify the presence of stated features, integers, steps, operations, elements, and/or components, but do not preclude the presence or addition of one or more other features, integers, steps, operations, elements, components, and/or groups thereof.

Aspects and elements of all of the embodiments disclosed above can be combined in any way and/or combination with aspects or elements of other embodiments to provide a plurality of additional embodiments.

In the drawings and specification, there have been disclosed typical embodiments of the invention and, although specific terms are employed, they are used in a generic and descriptive sense only and not for purposes of limitation, the scope of the invention being set forth in the following claims.

That which is claimed:

1. A flat panel antenna, comprising:

a plurality of flat panel arrays (FPAs) that are arranged adjacent one another, wherein ones of the plurality of FPAs are configured to be coupled to at least one radio to transmit and/or receive communication signals via respective data communication links in a plurality of

16

different respective frequency bands and/or at different respective polarizations; and
an enclosure that defines an internal cavity that includes the plurality of FPAs.

5 2. The flat panel antenna of claim 1, wherein the plurality of FPAs comprise a first FPA that is configured to transmit and/or receive communication signals having a vertical polarization and a second FPA that is configured to transmit and/or receive communication signals having a horizontal polarization.

10 3. The flat panel antenna of claim 1, wherein the plurality of FPAs comprise a first FPA that is configured to exclusively operate in a transmit mode and a second FPA that is configured to exclusively operate in a receive mode.

15 4. The flat panel antenna of claim 2, wherein the first FPA is configured to operate in a first frequency band and the second FPA is configured to operate in a second frequency band that is different from the first frequency band.

20 5. The flat panel antenna of claim 4, wherein the first frequency band and the second frequency band are narrow bands that have a frequency range of less than about 10 GHz.

25 6. The flat panel antenna of claim 5, wherein the first frequency band comprises a 71-76 GHz frequency band and the second frequency band comprises a 81-86 GHz frequency band.

7. The flat panel antenna of claim 5, wherein the plurality of FPAs are configured to transmit and/or receive communication signals in a wide frequency band that includes both 30 of the first frequency band and the second frequency band.

35 8. The flat panel antenna of claim 1, wherein the plurality of FPAs comprise:

a first FPA that is configured to operate in a first frequency band; and

35 a second FPA that is configured to operate in the first frequency band, wherein a polarization difference between the first FPA and the second FPA is about ninety degrees.

40 9. The flat panel antenna of claim 8, wherein the plurality of FPAs further comprise:

a third FPA that is configured to operate in a second frequency band; and

45 a fourth FPA that is configured to operate in the second frequency band, wherein a polarization difference between the third FPA and the fourth FPA is about ninety degrees.

10. The flat panel antenna of claim 1, wherein the plurality of FPAs comprise:

50 a first FPA that is configured to transmit or receive communication signals having a vertical polarization in a first frequency band;

a second FPA that is configured to transmit or receive communication signals having a horizontal polarization in the first frequency band;

55 a third FPA that is configured to transmit or receive communication signals having the vertical polarization in a second frequency band that is different from the first frequency band; and

60 a fourth FPA that is configured to transmit or receive communication signals having the horizontal polarization in the second frequency band.

11. The flat panel antenna of claim 10, wherein the at least one radio comprises a first radio and a second radio, wherein the first FPA and the third FPA are configured to be coupled to the first radio, and

65 wherein the second FPA and the fourth FPA are configured to be coupled to the second radio.

17

12. The flat panel antenna of claim 10, wherein the first FPA and the third FPA are configured to transmit the communication signals, and
wherein the second FPA and the fourth FPA are configured to receive the communication signals.

13. The flat panel antenna of claim 10, wherein the first, second, third and fourth FPAs are arranged in a two column, two row configuration, and
wherein the second FPA is in a first row and a first column,

the third FPA is in the first row and a second column, the fourth FPA is in a second row and the first column, and the first FPA is in the second row and the second column.

14. The flat panel antenna of claim 1, wherein each of the plurality of FPAs is a rectangular shaped FPA and has a polarization direction that extends diagonally across the rectangular shaped FPA from a first corner to a second corner that is opposite the first corner,
wherein the plurality of FPAs comprise:

a first FPA that is configured to transmit or receive communication signals having a vertical polarization in a first frequency band;

a second FPA that is configured to transmit or receive communication signals having a horizontal polarization in the first frequency band;

a third FPA that is configured to transmit or receive communication signals having the vertical polarization in a second frequency band that is different from the first frequency band; and

a fourth FPA that is configured to transmit or receive communication signals having the horizontal polarization in the second frequency band.

15. The flat panel antenna of claim 14, wherein the plurality of FPAs are arranged in a diamond shaped configuration, and
wherein the enclosure is substantially rectangular and is arranged such that a corner of each of the plurality of FPAs is positioned along a corresponding side of the enclosure.

16. The flat panel antenna of claim 14, wherein the plurality of FPAs are arranged in a diamond shaped configuration, and
wherein the enclosure is substantially diamond shaped and is arranged such that each corner of the enclosure is positioned adjacent a corner of a different one of the plurality of FPAs.

17. The flat panel antenna of claim 1, wherein the at least one radio comprises a first radio and a second radio, and wherein the plurality of FPAs comprise:

18

a first FPA that is configured to operate in a first frequency band; and
a second FPA that is configured to operate in a second frequency band that is different from the first frequency band,

the antenna further comprising:
the first radio that is coupled to the first FPA; the second radio that is coupled to the second FPA; and a diplexer that is coupled to the first radio and the second radio.

18. The flat panel antenna of claim 17, wherein the first frequency band and the second frequency band are each a narrow frequency band channel, and
wherein the diplexer is operable to combine a first frequency band channel from the first radio and a second frequency band channel from the second radio into a wideband channel in a receive mode.

19. The flat panel antenna of claim 17, wherein the first frequency band and the second frequency band are each a narrow frequency band channel, and
wherein the diplexer is operable to separate a wideband channel into a first frequency band channel and a second frequency band channel in a transmit mode.

20. The flat panel antenna of claim 1, further comprising at least one electromagnetic decoupling structure that is positioned adjacent one or more of the plurality of FPAs and that is configured to reduce electromagnetic interference between ones of the plurality of FPAs.

21. A method of manufacturing a flat panel antenna, the method comprising:

providing a plurality of flat panel arrays (FPAs) that are arranged adjacent one another, wherein ones of the plurality of FPAs are configured to be coupled to at least one radio to transmit and/or receive communication signals via respective data communication links in a plurality of different respective frequency bands and/or at different respective polarizations; and

providing an enclosure that defines an internal cavity that includes the plurality of FPAs.

22. The method of claim 21, wherein the plurality of FPAs comprise a first FPA that is configured to transmit and/or receive communication signals having a vertical polarization in a first frequency band, and a second FPA that is configured to transmit and/or receive communication signals having a horizontal polarization in a second frequency band that is different from the first frequency band.
